ABSTRACT OF THE DISCLOSURE

Dextrose is continuously crystallized from a massecuite in a crystal slurry which is continuously recycled between a hold-up tank and a tubular crystallizer and which has a mother liquor from a crystal separating centrifuge recycled to the crystallizer to control the percentage of crystals in the crystallization zone.

BACKGROUND OF THE INVENTION

Dextrose is conventionally crystallized from a massecuite in batch crystallizers which require 70 to 100 hours to grow crystals to the desired size of about 200 microns. This invention crystallizes dextrose (monohydrate or anhydrous) in a continuous process which is less costly, produces crystals with a desired average size distribution of at least 150 to 250 microns, and reduces residence time in the continuous crystallizer to less than 24 hours.

SUMMARY OF THE INVENTION

A massecuite is fed into a tubular crystallizer through which it passes into an agitated hold-up tank. A crystal slurry is recirculated from the hold-up tank back through the crystallizer to grow crystals to a desired size. Some of the crystal slurry is withdrawn from the hold-up tank and dextrose crystals, as a product, are separated from mother liquor. Some of the mother liquor is recirculated back into the crystallizer to reduce the percentage of crystals in the slurry and thus promote crystal growth in the crystallizer and the hold-up tank.

BRIEF DESCRIPTION OF THE DRAWING

FIGURE 1 is a schematic drawing showing apparatus used in the process of this invention; and

FIGURE 2 is a phase diagram for dextrose and water.

DESCRIPTION OF THE PREFERRED EMBODIMENT

As shown in FIGURE 1, massecuite at 140° to 160° F. with a concentration of about 80 percent dextrose flows from feed pipe 10 into feed tank 11. By means of pipes 12 and 13 and pump 14, feed is introduced into the crystallizer 15.

Crystallizer 15 is of the tubular type having a central tube 16 to contain the feed and an outer cooling jacket 17 into which cooling water enters through pipe 18 and from which the cooling water exits through pipe 19. Disposed within central tube 16 is a shaft 20 which is oscillated by a motor drive 21. Agitator blades 22 are mounted on shaft 21 to extend with a slight clearance from the walls of tube 19. The blades 22 are oscillated to sweep past a given point on the walls of tube 19 at a rate of 20 to 45 cycles per minute. This agitation ensures a high heat transfer rate from the viscous feed to the walls of tube 16.

Feed with crystals forming therein flows from crystallizer 15 through pipe 24 into hold-up tank 25 which

2

is equipped with an agitator 26 driven by motor 27 to maintain crystals within the feed in suspension as a slurry. Pipe 28, pump 29, and pipe 30 recycle crystal slurry from hold-up tank 25 back into feed entering crystallizer. Effluent crystal slurry flows from tank 25 through pipe 31 to centrifuge 32. Crystal water enters centrifuge 32 through pipe 33; crystals are removed as a product through pipe 34; and, mother liquor flows from centrifuge 32 through pipe 35.

10 The agitator 26 maintains crystals in tank 25 in suspension where crystals continue to grow in the cooled slurry. The volume of hold-up tank 25 is related to the residence time required to grow crystals of a desired average size of 200 to 300 microns. In the process of this invention, the residence time is less than 24 hours and the volume of the crystallizer 15 should be less than 1/6 the total volume required for such residence time. Thus, the hold-up tank should have a capacity at least five times that of the crystallizer 15.

20 Centrifuge 32 is preferably a high speed centrifuge having a perforated basket with a screw type crystal advancing apparatus turning 5 to 15 r.p.m. faster than the basket. If desired, other equivalent types of centrifuges or separation apparatus may be used.

25 Mother liquor from centrifuge 32 passes through pipe 35 to the mother liquor tank 36. Pump 37 recycles mother liquor through pipes 38 and 39 to feed tank 11. The recycle of mother liquor into the feed tank 11 adds mother liquor to the feed. Since substantially all the dextrose has been crystallized from the recycled mother liquor, it will reduce the percentage of crystals by weight in the slurry which enters the crystallizer 15 through pipe 30. This renders the slurry in crystallizer 15 less viscous to improve heat transfer and crystal growth in the slurry.

30 35 For best results, the slurry entering crystallizer 15 should contain 25 to 45 percent crystals by weight. This percentage is controlled by the amount of mother liquor recycled from tank 36. Effluent mother liquor flows from tank 36 through pipe 40 and may be further processed and sold as a syrup.

35 As an example of this invention, a system with a residence time of 12 hours was operated for one week on a continuous basis. The feed composition was 74 percent dextrose with 6 percent impurities in the form of higher sugars and 20 percent water. The slurry recycle rate was eight times the feed rate and the mother liquor recycle rate was 25 percent of the feed rate. The feed entered at a temperature of 140° to 160° F. and was crystallized at 115° F. for the production of dextrose monohydrate crystals. Crystals of approximately 200 microns in size were continuously produced.

40 45 As may be seen from FIGURE 2, a change in crystallization temperatures will produce monohydrate dextrose crystals if desired. It is to be pointed out that crystal growth takes place both in the crystallizer 15 and in the hold-up tank 25. To grow crystals of the desired size, the recirculation rate of the slurry should be between 4 and 15 times the feed rate from tank 11.

50 55 60 What is claimed is:

1. A process for the continuous crystallization of a dextrose from a massecuite comprising the steps of:
  - (a) passing a feed of a massecuite through a crystallizer into an agitated hold-up tank to form a dextrose crystal slurry,
  - (b) recirculating the slurry from the agitated hold-up tank through the crystallizer at a rate of at least four times the feed rate to continue the growth of dextrose crystals therein,
  - (c) withdrawing some of the slurry from the hold-up tank to a crystal separating device separating dextrose crystals from mother liquor, and

- (d) recycling at least some of the mother liquor into the feed to reduce the percentage by weight of dextrose crystals entering the crystallizer.
2. The process according to claim 1 wherein mother liquor is recycled reducing the percentage by weight of dextrose crystals entering the crystallizer to between 25 and 45 percent.
3. The process according to claim 2 wherein residence time in said process is less than 24 hours and dextrose crystals separated from mother liquor have an average size of 200 microns.
4. The process according to claim 3 wherein the feed is passed through a tubular crystallizer containing an agitator oscillating between 20 to 45 cycles per minute.
